UNITED STATES PATENT OFFICE.

WILLIAM E. DEAN, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FEED-VALVE DEVICE.

Application filed November 13, 1925. Serial No. 68,853.

This invention relates to pressure regulating valve devices, and more particularly to a feed valve device for maintaining the pressure in the brake pipe of a fluid pressure 5 brake system at a predetermined degree.

The standard feed valve device at present employed in connection with fluid pressure 10 brake systems, comprises a fluid pressure supply portion having a piston adapted to be operated upon a reduction in fluid pressure to actuate a supply valve, and a regulating portion which operates to effect a reduction in fluid pressure on said supply piston when the pressure in the brake pipe falls 15 below a predetermined degree.

In order to improve the operation of the feed valve device, it has heretofore been proposed to provide means for accelerating the action of the regulating portion by introducing 20 a Venturi tube, which is so disposed that the flow of fluid from the supply portion to the brake pipe causes a suction effect on the regulating portion and thereby accelerates the action of said regulating portion by reducing the pressure thereon to a 25 degree less than the pressure existing in the brake pipe.

When a Venturi tube is employed in the feed valve device for the above purpose, it 30 has been found that the accelerating action is apt to be excessive and is liable to cause an overcharging of the brake pipe.

The principal object of my invention is to 35 provide a feed valve device having a Venturi tube for the above purpose, and means for preventing an excessive accelerating action of the Venturi tube.

In the accompanying drawing, the single 40 figure is a central sectional view of a feed valve device embodying my invention.

As shown in the drawing, the feed valve device may comprise a casing 1, containing a fluid pressure supply portion and a regulating portion. The regulating portion comprises 45 a diaphragm 2 subject on one side to the pressure of an adjustable spring 3 and on the other side to the pressure of the brake pipe 4 or other outlet pressure. Said diaphragm is adapted to operate a valve 5 for venting fluid from the fluid pressure supply portion.

The supply portion comprises a piston 6, contained in piston chamber 7, and a slide

valve 8, contained in valve chamber 9, and adapted to be operated by piston 6.

The supply valve 8 is provided with two supply ports 10 and 11 adapted to register respectively with ports 12 and 13, when the slide valve is moved outwardly by the piston 6, and interposed in the passage connecting the ports 12 and 13 with the brake pipe 4 is a Venturi tube device 14 which provides communication from the brake pipe 4 through passage 15 to the diaphragm 2 of the regulating portion and which operates according to the rate of flow of fluid from the supply valve 8 to the brake pipe to cause a suction effect, so as to reduce the pressure of fluid acting on the diaphragm 2.

The port 11 is positioned to partly register 70 with port 13 slightly before the port 10 commences to register with port 12, and according to my invention, two springs are provided to oppose the outward movement of piston 6. The spring 16 opposes movement 75 from the initial inner position, while spring 17 is adapted to oppose movement of the piston 6 only when the piston has moved the slide valve 8, so that port 11 partly registers with port 13 and before the port 10 commences to register with port 12.

In operation, fluid under pressure from main reservoir 18 or other source of pressure flows through pipe 19 to valve chamber 9 and thence through passage 20 and a restricted port 21 to piston chamber 7. If valve 5 is in its seated position, the fluid pressures on opposite sides of piston 6 are permitted to equalize, and spring 16 then maintains the piston 6 in its inner position, as 85 shown in the drawing.

If the pressure in the brake pipe 4 should fall below the pressure at which the spring 3 of the regulating portion may be adjusted, the reduced pressure on diaphragm 2 permits the spring 3 to move the diaphragm so as to effect the opening of the valve 5. Fluid under pressure is then vented from piston chamber 7 to passage 15 and piston 6 is moved outwardly by the higher pressure in valve 100 chamber 9, compressing the spring 16.

The slide valve 8 moves out until the port 11 commences to register with port 13, and for light reductions in brake pipe pressure the flow through the ports 11 and 13 may be 105 sufficient to compensate for the fall in brake

pipe pressure. If the drop in brake pipe pressure is such as to cause a greater reduction in pressure on the diaphragm 2 and a consequent wider opening of the valve 5, then the piston 6 will be moved out so that both ports 10 and 11 will register with the ports 12 and 13. This causes a greater flow of fluid from the supply portion to the brake pipe and correspondingly increased suction action of the 10 Venturi tube 14, which tends to accelerate the action of the regulating portion, by increasing the rate of reduction in pressure on the regulating diaphragm 2. This acceleration of the action of the regulating portion is partly 15 neutralized, however, by the action of the spring 17, which opposes the further outward movement of the piston 6, so that if the springs 16 and 17 are properly proportioned, excessive acceleration of the operation of the 20 regulating portion by the action of the Venturi tube is prevented.

Having now described my invention, what I claim as new and desire to secure by Letters Patent, is:—

25 1. The combination with a source of fluid underpressure and a brake pipe, of a feed valve device comprising a supply valve for controlling the supply of fluid under pressure from said source to the brake pipe, a piston 30 for operating said valve, a Venturi device disposed in the passage through which said sup-

ply valve supplies fluid to the brake pipe, a regulating valve for venting fluid from said piston, and a flexible diaphragm having a passage connected to the suction of said Venturi device for operating said regulating valve, said regulating valve controlling communication from said piston to said suction passage.

2. The combination with a source of fluid 40 under pressure and a brake pipe, of a feed valve device comprising a supply valve for controlling the supply of fluid under pressure from said source to the brake pipe, a piston for operating said valve, a spring for opposing movement of said piston, a second spring operative upon a predetermined movement of said piston for opposing further movement of said piston, a Venturi device disposed in the passage through which said supply valve supplies fluid to the brake pipe, a regulating valve for venting fluid from said piston, and a flexible diaphragm having a passage connected to the suction of said Venturi device for operating said regulating valve, said regulating valve controlling communication from said piston to the passage 45 connected to the suction of the Venturi device.

50 In testimony whereof I have hereunto set my hand.

WILLIAM E. DEAN.
